WELL DRILLING APPARATUS

George Heinish, Akron, Ohio, assignor to The Star
Drilling Machine Company, Akron, Ohio, a
corporation of Ohio

Application June 21, 1939, Serial No. 280,341

13 Claims. (Cl. 255—16)

This invention relates to well drilling apparatus of the type that comprises spudding mechanism, and more especially it relates to improvements in the control of the recoil of the spudder shock absorbing mechanism such as occurs following the stroke or drop of the bit or drilling tool.

The invention is an improvement upon the well drilling apparatus constituting the subject matter of my prior U. S. Patent No. 2,145,352, issued

January 31, 1939.

It has been found that in the drilling of a well with cable tools, the natural period of vibration and load cycle varies according to the increased depth to which the well is drilled. Since the customary shock absorbing mechanism has a definite recoil or vibration period inherent to itself, it is obvious that without some means to alter this constant period, the shock absorber will not remain properly timed with the natural action of the tools.

Hence, one of the chief objects of the invention is to provide means on a drilling apparatus to change certain of the normal characteristics of the customary resilient shock absorbing mechanism, so as to maintain a properly timed or synchronized relationship between the tools and the shock absorber.

It has also been found that when the tools become stuck in a hole it is necessary to jar them loose, which operation can best be accomplished by eliminating the normal action of the shock absorbing mechanism; therefore another object of the invention is to utilize the same means that is used for adjusting the recoil of the shock absorbing mechanism substantially, or even completely, to eliminate said normal shock absorbing action.

Other objects of the invention are to eliminate shock peak loads; to reduce the strain on the drilling line; to make possible the use of equipment of light weight construction; to provide a construction which enables faster drilling; to protect the machine against jars and jolts; and to reduce the number of "fishing" jobs due to broken drill lines. Further objects will be manifest as the description proceeds.

Of the accompanying drawings:

Fig. 1 is a vertical section through one of a pair of spudder arms, the parts thereof being in the relative positions they occupy when the free end of the arm as a whole is depressed to raise the bit or drilling tool, said section being taken substantially on the line 1—1 of Fig. 2;

Fig. 2 is a plan view of one of the spudder arms; Fig. 3 is a section, on a larger scale, of the free

end of the spudder arm shown in Fig. 1, the parts thereof being in the relative positions they occupy when the free end of the spudder arm is elevated, to lower the drilling tool and with the resilient member of the shock absorbing mechanism under full compression;

Fig. 4 is a section similar to Fig. 3, the parts thereof being in the intermediate positions they assume in taking up slack in the drill line following the dropping of the drilling tools.

Fig. 5 is a section on the line 5—5 of Fig. 1;

Fig. 6 is a perspective view of a valve element of the apparatus;

Fig. 7 is an end view of the structure shown in Figure 6, as seen from the right thereof; and

Fig. 8 is a fragmentary section on the line 8—8 of Fig. 1.

Referring to the drawings, the improved recoil control mechanism is shown in operative combination with the spudder mechanism of the apparatus. The frame on which the spudder is mounted, including the mast and the reciprocating mechanism that operates the spudder arm, may be of any known or preferred construction, but preferably is of the same general type as that shown in my prior U. S. patent aforementioned, reference being directed to said patent for associated structure not shown herein.

The spudding mechanism comprises a pair of pivotally mounted arms that operate in unison for the same purpose, said arms being of identical construction so that a description of one will suffice for both. Obviously, however, a single arm could be used and still utilize the features of this invention. One of the spudder arms, generally designated 10, is shown substantially in its entirety in Figs. 1 and 2. Said arm comprises a pair of metal tubes 11, 11 arranged parallel to each other in a vertical plane, the rear ends of said tubes having a common end-flange 12 permanently secured thereto as by welding, there being an end cap 13 bolted to said end-flange. At their opposite or front ends the tubes 11 extend into and are permanently united with a hollow housing structure consisting of two parts, the rear part being designated 14 and being secured to said tubes, the forward part being designated 15 and being bolted to the part 14. Near their rear ends, adjacent end-flange 12, the tubes 11 are encircled by a collar 16 that is permanently secured thereto, said collar carrying laterally projecting trunnions 17 at each side thereof. Said trunnions are receivable in suitable journals (not shown) on the frame of the apparatus and constitute the axis about which the spudder oscillates.

Oscillation of the spudder arms is effected by means of a pair of spaced pitmans, such as the pitman 18, which pitmans are pivotally connected at one end to a bracket 19 that is connected to 5 both spudder arms as presently will be explained, the opposite ends of the pitmans being pivotally connected to respective rotatable crank arms (not shown) as is common practice in the art. The arrangement of the double pitmans serves to balance the load in the center of the apparatus.

The end cap 13 is formed with a pair of parallel fixed bearings 21, 21 that are co-axially disposed with relation to the respective tubes 11, said bearings slidably receiving one end portion 15 of respective tubular spindles 22. The opposite ends of said spindles are permanently secured, by welding or any other suitable means, in one end of respective co-axial tubular slides 23, which slides are of somewhat larger diameter 20 than the spindles, and are journaled for axial movement in respective bearings 24 in the housing structure 14. Secured to the opposite ends of slides 23 is a bracket or cap 25, the latter being so constructed as to give access to the interior of 25 the slides for a purpose presently to be explained. Each spindle 22 has a slidable spacing collar 26 mounted thereon intermediate its ends, and a coiled compression spring 27 is mounted upon the spindle between said collar and the rear face of 30 a slide 23. A second compression spring 28 is mounted upon each spindle 22 between the collar 26 and the end cap 13. The latter is apertured as at 29, 29, Fig. 1 to enable the passage 35 of fluid from the interior of the spindles 22 into the space between said spindles and the respective tubes 11, where said fluid may immerse the springs 27, 28. The end cap 13 is provided with drain openings 30, 30 to enable fluid to be withdrawn from the spudder arm at the pivoted end 40 thereof.

Pivots mounted upon a transverse hinge pin 32 in the cap 25 is a floating shoe designated as a whole by the numeral 33, a portion of said shoe being formed with an arcuate surface 34, the latter being engaged by the complimentarily arcuate surface 35 of a cam structure 36. The cam structure 36 is pivotally mounted for angular movement about an axis that is eccentrically positioned with relation to the axis of the arcuate 45 cam surface 35, the arrangement being such that angular movement of the structure 36 about its axis will cause it to move toward the floating shoe 33 and force the latter, and elements connected thereto, rearwardly against the opposing 50 force of the springs 27, 28, the cam surface 35 sliding relatively of the arcuate surface 34 during such movement of the cam structure. It will be seen that the cam structure 35 applies a variable leverage to the springs 27, 28, and thereby increases the resistance of the springs in direct proportion to the intensity of the shock load in the 55 same manner disclosed in my aforesaid patent.

As is best shown in Fig. 8, the cam structure 36 is formed at its axis of rotation with laterally 60 extending trunnions 36a, the latter being journaled in bearings 38. At one side of the cam structure the bearings 38 are carried by a bearing plate 39, Fig. 2, that is suitably bolted to the housing sections 14, 15 at the juncture thereof. 65 At the other side of the same structure the bearings 38 are carried by a structure 19a that is an integral part of the bracket 19 previously described, said structure 19a being bolted to the housing sections 14, 15 in the same manner as bearing plate 39. There are oil seals, such as the

70 seal 40, Fig. 8, mounted between the plate 39 and structure 19a and the respective trunnions 36a of the cam structure 36.

For effecting angular movement of the cam structure 36, the trunnions 36a thereof are extended outwardly of the oil seals 40, and mounted upon the end portion of each trunnion is an arm 42, that projects forwardly beyond the forward end of the spudder. The two arms 42 of each spudder arm support the respective end portions of a spudding shaft 43. Journaled on the spudding shaft 43 between the two pairs of arms 42 is a peripherally grooved spudding sheave 44 about which is trained the drilling line 45. The spudding sheave 44 is provided with a 16 guard 46 that is carried by bracket arms 47, 47 mounted on spudder shaft 43 at each side of sheave 44, said guard being guided by a guide rod 48 below the sheave. The rod 48 is supported by bracket arms 49 that are carried by arms 42 of 20 the opposite spudder arms. The bracket arms 47 may be locked to the shaft 43 in the center thereof for fast spudding, or they may be permitted to move laterally for perfect spooling of the drill line 45 when drilling deep wells. From 25 the foregoing it will be seen that when drilling, the shock load from the drill line is transmitted through the spudding sheave to the spudder shaft, and from the latter by means of arms 42 through the cam structure 36 and shoe 33 to the 30 springs 27, 28.

The spudder arm also carries the usual heel sheave 50 that guides the drill line 45 from the spudding sheave 44 to the bull reel (not shown). The heel sheave 50 is journaled upon a heel shaft 36 51 that is supported at its respective ends by brackets 52 permanently secured to the respective spudder arms, forwardly of the axis of oscillation thereof. The heel sheave 50 is provided with a guard to retain the drill line therein, 40 which guard consists of a simple rod 53 positioned close to the periphery of the heel sheave and supported from its respective ends by brackets 54 attached to the respective brackets 52.

Shock load on the drill line 45 is cushioned 45 and absorbed by the springs 27, 28 in the manner previously described. However, uncontrolled recoil of said springs, after removal of said load, quickly reverses the movement of the spudding sheave, resulting in destroying the synchronization 50 of the movement of the tools and said springs. The feature of simple and efficient recoil control mechanism is a novel feature of this invention and constitutes its main advance over the prior U. S. Patent aforementioned.

Said recoil control mechanism consists of a shock absorber of the fluid type, said shock absorber comprising a cylinder 58 that is attached to the housing structure 15, between the arms 42, a part of said cylinder extending into the said housing and being open to the interior thereof, the outer end of said cylinder being closed. Mounted for axial reciprocatory movement in the cylinder 58 is a piston 59 carrying the usual wrist pin 60 to which is connected a piston rod 61, the other end of the latter being connected to the cam structure 36 through the agency of a pivot pin 62. The axis of the pivot pin 62 is coincident with the axis of the arcuate cam surface 35 of the cam structure 36. The arrangement is such 70 that the piston 59 is reciprocated in its cylinder 58 as the sheave arms 42 are moved between the two extreme positions shown in Fig. 1 and Fig. 3. The interior of the spudder arm, including the tubes 11, housing structures 14, 15, and the cylin- 75

der 58 are filled with a heavy lubricating liquid such as oil, the level of said liquid being indicated at 63, Figs. 1, 3 and 4. Suitably positioned filling and drainage ports 64, 64 are provided in the housing structure 15, and a similar port 65 is provided in the head of the cylinder 58.

The liquid in the spudder arm is utilized for retarding and cushioning the movement of the piston 59 as it moves from the position shown in Fig. 3 to the position shown in Fig. 1 and to this end suitable valve means are provided, one of said valve means being located in the piston, and another being located in the wall of cylinder 58. The valve means located in the piston is so arranged as automatically to open and enable liquid to pass through the piston when the latter is moving in the direction indicated by the arrow in Fig. 3, and automatically to close and prevent the passage of liquid through the piston when the latter is moving in the direction indicated by the arrow in Fig. 4. The valve means of the piston 59 comprises a valve plate 68 of general trefoil shape, which plate is slidably guided upon a square axial boss 59a on the outer end face of the piston 59, the lobes of said valve plate overlying respective arcuate apertures or ports 69 in the end wall of the piston. The valve plate 68 is yieldingly urged against the end face of the piston by three rods 70 that are connected at one end to the valve plate and extend through the ports 69 of the piston, the opposite end portions of rods 70 slidably extending through respective apertured ears 71, there being a compression spring 72 mounted upon each rod between the ear 71 and a cap, such as a nut and washer, on the adjacent end of the rod. When the piston 59 is moving in the direction indicated by the arrow in Fig. 3, the valve plate 68 will be forced away from the end face of the piston, against the force of springs 72, due to the partial vacuum set up in the outer end of the cylinder, such movement of the valve plate uncovering the ports or apertures 69 of the piston and enabling liquid to flow therethrough.

The valve means located in the cylinder 58 comprises a plug valve generally designated 75 and best shown in Figs. 5 to 7 inclusive. Said valve member 75 has a hexagon head 75a at one end thereof, a threaded portion 75b adjacent said head, and a smooth cylindrical portion 75c beyond said threaded portion. There is an axial bore 76 extending into the valve structure at the smooth end 75c thereof, and there is a radial bore 77 extending from the bore 76 to the outer surface of the plug. The portion 75c is formed with a circumferential groove 78 that intersects radial bore 77, the capacity of said groove for conducting fluid being substantially less than the capacity of bore 77. The cylinder 58 inclines downwardly toward its outer end, and at substantially the lowest point thereof is formed with a pair of internal, spaced-apart passages 80, 80 that are separated by an intervening wall, the latter being transversely bored at 81 to receive the smooth cylindrical portion 75c of the plug valve 75. The opposite walls of the cylinder casting at each side of passages 80 are bored and internally threaded at 82 to receive the threaded portion 75b of the plug valve, or alternatively, a closure plug 83, the arrangement being such that the head 75a may be positioned at either side of the cylinder head to suit the convenience of the operator. A lock nut 84 is threaded onto portion 75b of the valve structure 75 to retain the latter in properly adjusted position

in a bore 82. The cylinder 58 is formed with a radial bore 85 extending from its piston chamber to the transverse bore 81 therein, and when the plug valve 75 is in place, the bore 85 will be aligned with the groove 78 of the valve structure, or the bore 77 therein, according to the angular position of said plug valve. The head 75a of the plug valve may be engraved with suitable indicia, which indicia is determinately positioned with relation to the bore 77 of the valve, as shown in Fig. 7, to indicate whether or not said bore 77 is in direct communication with the bore 85 of the cylinder head, as shown in Figure 5. Suitable markings, such as arrows 86, 86, Fig. 5, may be cast on opposite sides of the cylinder 58 above the threaded bores 82 therein to facilitate the proper angular setting of the plug valve.

As previously stated, the plug valve 75 may be threaded into either bore 82 of the cylinder 58, the plug 83 being threaded into the other bore 82 to close the same. When the plug valve is so mounted, the axial bore 76 opens into one of the passages 80 in the cylinder casting 58, which passages are in communication with the interior of the housing structure 15 and hence are filled with the liquid with which the spudder arm is filled. When the bore 77 of the plug valve is in direct communication with the bore 85 of the cylinder 58 as shown in Fig. 5, liquid may flow therethrough into and out of the interior of said cylinder, but in a somewhat constricted course so that when the piston 59 is moving in the direction indicated by the arrow in Fig. 4, sufficient pressure is built up in the cylinder 58 to properly cushion the movement of the arms 42 and sheave 44 resulting from the rebound of the springs 27, 28, yet enabling the said springs to expand to their maximum extent during each complete oscillation of the spudder arm. This setting of the plug valve is employed during normal drilling operation.

Upon occasion it is desirable to jar the drill line, as when attempting to dislodge tools that have become stuck in the hold and also when fishing for lost drills after a drill line has broken. This requires an entirely different action of the spudder, and is accomplished by turning the plug valve 75 angularly to the desired extent up to 180°. Turning of the plug valve as described moves the bore 77 therein out of direct communication with the bore 85 of the cylinder casting, so that fluid passing into and out of the cylinder must traverse the greatly restricted groove 78 of the plug valve. The arrangement is such that the oil in the cylinder builds up sufficient pressure, upon recoil of the springs 27, 28 when the piston 59 is moving in the direction indicated by the arrow in Fig. 4, to prevent maximum outward movement of the piston during a complete operative cycle of the spudder arm, and thereby to prevent complete expansion or recoil of the springs 27, 28. The arrangement is such as to prevent the complete elimination of the spring action, and provides a means for determining the jarring load as well as an indicator to prevent serious overloads. If the plug valve is rotated only enough to vary the effective opening of the bore 77 with respect to the bore 85, the control of the recoil is varied from the minimum when the said bores are in alignment to the maximum when the bores are 180° apart. Obviously, if it is desired to completely eliminate the action of springs 27, 28, it is only necessary to provide a plug valve not having the groove 78 therein.

The combination of coil springs for absorbing

- the shock load with hydraulic control of the recoil of the springs results in a controlled drilling action that greatly contributes to faster drilling. The invention also makes possible a different and preferred action of the spudder arm when fishing for tools, and achieves the other advantages set out in the foregoing statement of objects.
- 5 Modification may be resorted to without departing from the spirit of the invention, or the 10 scope thereof as defined by the appended claims.
- 10 What is claimed is:
1. Well drilling apparatus comprising a spudder arm adapted for oscillatory movement, resilient cushioning means carried by said spudder arm, a 15 sheave mounted for pivotal movement with relation to said spudder arm, variable leverage mechanism carried by the spudder arm and operatively interposed between the sheave and said cushioning means, and hydraulic means oppos- 20 ing the recoil of said cushioning means.
  2. A combination as defined in claim 1 in which the hydraulic means is operatively associated with the variable leverage mechanism.
  3. A combination as defined in claim 1, includ- 25 ing valve means controlling the operation of the hydraulic means.
  4. Well drilling apparatus comprising a spudder arm adapted for oscillatory movement, a sheave-carrying arm pivotally mounted on said spudder 30 arm and adapted for angular movement relatively thereof, a resilient shock absorber carried by said spudder arm, cam means operatively interposed between said sheave arm and the shock absorber for operating the latter upon angular 35 movement of the sheave arm in one direction, and hydraulic means operatively connected to said cam and yieldingly opposing movement thereof as the result of reaction of said shock absorber.
  5. A combination as defined in claim 4 includ- 40 ing control means for varying the effectiveness of the hydraulic means.
  6. Well drilling apparatus comprising a spudder arm adapted for oscillatory movement, resilient cushioning means carried by said spudder arm, 45 and hydraulic means opposing the recoil of said cushioning means.

7. Well drilling apparatus comprising a spudder arm adapted for oscillatory movement, resilient cushioning means carried by said spudder arm, hydraulic means opposing the recoil of said cushioning means, and valve means controlling the 5 operation of said hydraulic means.

8. Well drilling apparatus comprising a drill line and means for operating the drill line, cushioning means interposed between the drill line and its operating means for cushioning the 10 shock of the drill line, and hydraulic means oppos- 15 ing the recoil of said cushioning means.

9. Well drilling apparatus comprising a drill line and means for operating the same, cushioning means interposed between the drill line and 15 its operating means for cushioning the shock of the drill line, hydraulic means opposing the recoil of said cushioning means, and valve means controlling the operation of said hydraulic means.

10. Well drilling apparatus comprising a drill 20 line and means for operating the same, said line-operating means comprising a sheave about which the line is trained, cushioning means operatively associated with said sheave for cushioning the shock of said drill line, and hydraulic means oppos- 25 ing the recoil of said cushioning means.

11. A combination as defined in claim 10 includ- 30 ing valve means for controlling the operation of the hydraulic means.

12. Well drilling apparatus comprising a drill 35 line and means for operating the same, cushioning means normally operating to cushion the shock of said drill line, and hydraulic means for preventing the functioning of said cushioning means to meet abnormal conditions of drilling. 35

13. Well drilling apparatus comprising a drill line and means for operating the same, cushioning means normally operating to cushion the shock of the drill line, hydraulic means normally controlling the recoil of said cushioning means, 40 and means for utilizing the said hydraulic means to prevent the functioning of the cushioning means.

GEORGE HEINISH.
